UNITED STATES PATENT OFFICE

JACK SCHWEIZER, OF NEW YORK, N. Y.

DESIGN FOR A COMBINED RADIATOR AND HEADLIGHTS OR THE LIKE ARTICLE

Application filed November 2, 1932. Serial No. 45,703. Term of patent 14 years.

To all whom it may concern:

Be it known that I, JACK SCHWEIZER, a citizen of Switzerland, residing at New York, in the county of New York and State of New York, have invented a new, original, and ornamental Design for a Combined Radiator and Headlights or the Like Article, reference being had to the accompanying drawing, forming part thereof.

Figure 1 is a front elevation of the com-

bined radiator and headlights showing my new design.

Figure 2 is a side elevation thereof, the radiator filler cap being omitted, and

Figure 3 is a perspective view.

I claim:

The ornamental design for a combined radiator and headlights or like article, as shown.

JACK SCHWEIZER.
